HOLDER FOR SPOOLS OF WRAPPING CORD

Jack G. Inman, Carrollton, Ill.

Application February 3, 1951, Serial No. 209,291

5 Claims. (Cl. 242—128)

1

This invention relates generally to holders for wrapping cord and more specifically to such a device which is adapted for use in association with a counter, or other support, on which packages are wrapped, the predominant object of the invention being to provide such a holder for spools of wrapping cord that may be secured to the counter or other support with which it is associated in such manner that the spool of cord is disposed out of sight beneath the counter, or other support, and with only an ornate cord dispensing portion appearing above the counter, or other support.

Fig. 1 is a front elevational view illustrating one of the holders for spools of wrapping cord of the present invention, a portion of an element by which the holder is supported being shown in Fig. 1.

Fig. 2 is an enlarged vertical section taken on line 2—2 of Fig. 1.

Fig. 3 is an enlarged horizontal section taken on line 3—3 of Fig. 2.

In the drawing, wherein is shown for purposes of illustration, merely, one embodiment of the invention, A designates generally the improved holder for spools of wrapping cord of this invention. The holder A includes a tubular member 1 which is exteriorly screwthreaded throughout its upper portion, as indicated at 1a in Fig. 2, said upper screwthreaded portion 1a of said tubular member 1 having screwthreadedly mounted thereon a nut 2 with which is associated a washer 3. The upper portion of the tubular member 1 is extended through an opening B' formed through a counter B, or other supporting structure. By referring to Fig. 2 it will be noted that the washer 3 contacts with a lower face portion of the structure B, there being a second washer 4 which embraces the upper portion of tubular member 1 and which contacts with a top face portion of the structure B. A coupling 5 is screwthreadedly applied to the extreme upper end portion of the tubular member 1, as is shown in Fig. 2, and the lower face of this coupling 5 contacts forcibly with the top face 45 of the washer 4. Also, the upper portion of the coupling 5 is provided with a screwthreaded recess 5a which screwthreadedly receives the lower screwthreaded end portion of a tubular element 6 of gooseneck formation.

The tubular member 1 is externally screwthreaded at its lower end portion, as indicated at 1b in Fig. 2, and this lower screwthreaded portion of said tubular member 1 screwthreadedly receives a sleeve 7 which is provided with a bore

7' that communicates with the opening through the tubular member 1. The top face of the sleeve 7 supports a spool S of cord, said spool having a tapered core S about which the cord is wound, and the lower edge of said tapered core contacting with the top face of the sleeve 7 (Fig. 2). The tubular member 1 has mounted thereon a collar 8 which preferably, though not necessarily is provided with a circumferential groove 8'. Also, an annular groove 9 is formed in the face of the bore of the collar 8, and disposed in this groove 9 is a split ring 10 formed of spring material. The split ring 10 tends to contact, or reduce its diameter, and as a result of this situation said split ring grips the circumferential face of the tubular member 1 in a manner to maintain said collar in a desired stationary position relative to said tubular member. Peripheral portions of the collar 8 contact with the inner face of the core of the spool S of cord so as to center said spool with respect to the tubular member 1.

In applying the improved holder to a counter B, or other supporting structure, the opening B' is formed through the structure and the coupling 5 and the tubular element 6 are removed from the upper end portion of the tubular member 1 and said upper portion of said tubular member is extended upwardly through the opening B' of the structure B. The coupling 5 with the tubular element 6 associated therewith is screwthreadedly applied to the upper portion of tubular member 1, and the nut 2 is drawn up on the screwthreaded portion 1a of the tubular member 1 so as to cause the washers 3 and 4 to tightly engage top and bottom face portions of the structure B located adjacent to the opening B' formed therethrough. Also, to apply a spool S of cord to the holder A the sleeve 7 is removed from the lower end of the tubular member 1 and the spool is moved upwardly of the tubular member 1 in embracing relation with respect thereto. The sleeve 7 is then re-applied to the lower portion of the tubular member 1 so that the lower edge of the core S may engage and be supported by the top face of said sleeve 7, and the collar 8 is positioned within the core of the spool so that an inner face portion of said core is engaged by a circumferential portion of said collar to properly center the spool relative to the tubular member 1. When the spool S has been assembled with respect to the tubular member, the cord extends from the spool S to the lower end of the sleeve 7, said cord passing through the bore of the sleeve 7, through the tubular member 1, through the bore 5b of the coupling 5, and through the tubular element 6,

from the upper end of which said cord normally hangs, as is shown in Fig. 2.

I claim:

1. A holder for a spool of wrapping cord comprising a tubular member having an upper portion thereof extended through an opening formed through a part of a structure by which the holder is supported, means for securing said tubular member to said structure, means mounted on said tubular member for supporting a spool of wrapping cord thereon beneath said structure, and a tubular element connected to said tubular member and disposed above said structure with which the holder is associated, said means for securing said tubular member to said structure comprising a coupling which connects said tubular member and said tubular element and abuts against an upper part of said structure, and a nut mounted on said tubular member which abuts against a lower part of said structure.

2. A holder for a spool of wrapping cord comprising a tubular member having an upper portion thereof extended through an opening formed through a part of a structure by which the holder is supported, means for securing said tubular member to said structure, means mounted on said tubular member for supporting a spool of wrapping cord thereon beneath said structure, a tubular element connected to and comprising a continuation of said tubular member and disposed above said structure with which the holder is associated, said means for securing said tubular member to said structure comprising a coupling which connects said tubular member and said tubular element and abuts against an upper part of said structure, and a nut mounted on said tubular member which abuts against a lower part of said structure, and a member supported by said tubular member for engaging and centering a spool of wrapping cord thereon.

3. A holder for a spool of wrapping cord comprising a tubular member having an upper portion thereof extended through an opening formed through a part of a structure by which the holder is supported, means for securing said tubular member to said structure, means mounted on said tubular member for supporting a spool of wrapping cord thereon beneath said structure, a tubular element connected to and comprising a continuation of said tubular member and disposed above said structure with which the holder is associated, said means for securing said tubular member to said structure comprising a coupling which connects said tubular member and said tubular element and abuts against an upper part of said structure, and a nut mounted on said tubular member which abuts against a lower part of said structure, and a member in the form of a collar supported by said tubular member for engaging and centering a spool of wrapping cord thereon.

4. A holder for a spool of wrapping cord com-

prising a tubular member having an upper portion thereof extended through an opening formed through a part of a structure by which the holder is supported, means for securing said tubular member to said structure, means mounted on said tubular member for supporting a spool of wrapping cord thereon beneath said structure, a tubular element connected to said tubular member and disposed above said structure with which the holder is associated, said means for securing said tubular member to said structure comprising a coupling which connects said tubular member and said tubular element and abuts against an upper part of said structure, and a nut mounted on said tubular member which abuts against a lower part of said structure, a member in the form of a collar supported by said tubular member for engaging and centering a spool of wrapping cord thereon, and spring means supported by said collar for frictionally engaging said tubular member so as to maintain said collar in positions on said tubular member to which it is adjusted.

5. A holder for a spool of wrapping cord comprising a tubular member having an upper portion thereof extended through an opening formed through a part of a structure by which the holder is supported, means for securing said tubular member to said structure, means mounted on said tubular member for supporting a spool of wrapping cord thereon beneath said structure, a tubular element connected to said tubular member and disposed above said structure with which the holder is associated, said means for securing said tubular member to said structure comprising a coupling which connects said tubular member and said tubular element and abuts against an upper part of said structure, and a nut mounted on said tubular member which abuts against a lower part of said structure, a member in the form of a collar supported by said tubular member for engaging and centering a spool of wrapping cord thereon, spring means related to said collar for frictionally engaging said tubular member so as to maintain said collar in positions on said tubular member to which it is adjusted, said spring means comprising a split ring formed of resilient material, and an annular groove formed in the annular face of said collar in which groove said spring means is disposed.
